UNITED STATES PATENT OFFICE.

ANNE E. MORGAN, OF WELLESLEY, MASSACHUSETTS.

GAME APPARATUS.

SPECIFICATION forming part of Letters Patent No. 613,383, dated November 1, 1898:

Application filed February 18, 1897. Serial No. 623,940. (No model.)

To all whom it may concern:

Be it known that I, ANNE E. MORGAN, a citizen of the United States, residing at Wellesley, in the county of Norfolk and State of Massachusetts, have invented a new and useful Game Apparatus, of which the following is a full, clear, and exact description.

My improvement in game apparatus is particularly designed to serve in a game of my own invention, which I have named the "Bellecycle." The purpose of this game is to oppose and overcome that nervous contraction which induces delay in physical circulation, muscular inefficiency, loss of courage, and hence loss of enthusiasm in recreation. This nervous contraction is overcome by, in the first place, an arrangement of apparatus which presents to the eye such combinations and sequences of color as at the same time shall be most restful and stimulating to the optic nerve; second, by such a sequence of motions as shall best vary the skill and muscular exertion of the individual, and, third, by alternating the phases of aim required by the person engaged in the game. In accomplishing these results I have devised the apparatus illustrated in the accompanying drawings, in which—

Figure 1 is a perspective view of my target. Fig. 2 is a view of a nest of the rings designed to be thrown at this target. Fig. 3 is an elevation of an improved form of my target. Fig. 4 is a sectional view of the same packed for storage or transportation, and Fig. 5 is a view of a detail thereof.

Referring to the drawings, A is a field adapted by means of a cord and pulley or other means to be hung at varying heights upon a wall, tree, or other object. This field is either rectangular, as shown in Fig. 1, or circular in outline, as shown in Fig. 3. The latter is, however, the shape which I prefer for reasons set forth later on. The chief function of the field A is that of a support for the rod C, upon whose outer extremity is fastened the semicircular target-head B. To the under side of this target-head is suspended a ring d, and to the under periphery of said ring is attached one end of the netting E, the other end of which is made fast to the field A. The diameter of said ring is made slightly larger than the largest of the nest of rings D,

(shown in Fig. 2,) while the diameter of the target-head B is made slightly less than the smallest of said rings. The object of thus arranging the relative sizes of the rings and target-head is to cause the rings D to be thrown over the said head with increasing difficulty as the smaller rings are used, and, further, to cause the same rings to be thrown through the ring d with increasing difficulty as the larger rings are used. In this way I accomplish a variation in the sequence of skill and muscular exertion with the different rings. The ring which is the smallest, and can hence be thrown with the least muscular effort, will be the hardest to pass over the target-head, but the easiest to pass through the ring d. On the other hand, the ring D, which is the largest, and consequently heaviest, will be the easiest to throw over said head and the most difficult to pass through the ring d.

The object of the netting E is to receive the rings D which have been thrown through the ring d and hold them to the end of each round of the game. They can be then removed and the game value of each and the total number of them jotted down by the tally-keeper. This separation and preservation of the rings until they can be counted is a great saving of time and care and is also, I find, a means for diminishing the tension upon the nerves of the person playing. To successfully pass a ring through the ring d and cause it to sink restfully upon the netting is a much more restful feature than if every ring had to go tumbling to the ground. In this respect the netting serves the same purpose as does the rod C, supporting the target-head B. Every ring successfully passed over the target-head comes to rest, of course, upon the rod C and is held thereby from falling to the ground.

In Fig. 1 the netting E is shown as attached to the ring d and to the field A by means of hooks d" and e, which permit of the disconnection of said netting from the ring and field. Such fastenings may, however, be permanent in character, closed eyelets taking the place of hooks, as indicated in Fig. 3. In Fig. 1 is further shown an attachment for securing the ring d to the target-head B differing somewhat from that in Fig. 3. In the former I represent two sets of hooks and eyes

b d', by which said ring is attachable to the said head at two points. My preferable construction is that of Figs. 3 and 5. Here the ring itself engages a single large hook *b* and is retained therein against the impact of the thrown rings by means of the leaf-spring *b'*, which can be easily raised when it is wished to remove the ring therefrom.

My method of vertically adjusting the field 10 A, and therefore the height of the target, comprises simply the cord *a'*, pulley and supporting-nail *a* T, and a cleat *a*². By this convenient arrangement the height of the target is adjusted to bring either the target-head B or the ring *d*, according to which is being used at that moment, with their centers upon the level of the player's eye. Furthermore, as the game progresses the target is moved to a higher and higher elevation, each 20 time increasing the difficulty of lodging the rings upon the rod and netting.

A further improvement, which I have embodied in the construction illustrated in Figs. 3 and 4, is in the means for enabling the entire game apparatus to be packed into a small compass. The field A being circular and of slightly greater diameter than the ring *d*, which is, it will be remembered, somewhat larger than the largest of the rings D, they 30 all can be placed one within the other upon said field and retained in place by the raised rim A', fastened upon the periphery of said field. This rim I prefer to form, for the sake of lightness and strength, from interwoven strands of reed or similar material. The rod C, which is secured to the field A by means of a screw C', can be unfastened and it and the target-head laid upon the field and the rings. The netting E is then brought over 40 the said parts and fastened to the back of the field, thereby making the whole secure.

In using this game apparatus the target is first suspended at a height which shall bring the center of the target-ring substantially opposite the eyes of the player. The player stands at a distance from the target equal to his stature plus the length of the cues with which he throws the rings. The first play aims to pass the entire series of rings one by 50 one, from the smallest to the largest in sequence, through the target-rings into the netting or pocket E. In case of entire success the player passes to the second test without competition. For this second play the target-ring is detached from the target-head and turned down against the wall or suspended from the rod C back against the field A. The player now aims to pass the entire series of rings in reverse order over the target-head, 55 beginning with the largest. In the first instance the largest ring tallies the largest number of game-credits or score, while in the second step the smallest ring scores the highest. In this way, as previously described, the sequence of skill and muscular exertion is continually varied and the tension upon the nerves of the player changed accordingly un-

til a nerve relaxation comes to take the place of the harmful nerve tension. Another pleasing and restful feature consists in coloring the 70 rings D differently one from the other—for instance, more or less of the primary or prismatic colors can be used, as indigo, blue, green, yellow, orange, and red for the six rings shown in Fig. 2. Of course these colors can 75 not be shown in the drawings, and I do not attempt to indicate them, but simply refer to the same as one of the features of the game in which I use my apparatus. By thus varying the sizes of the rings and alternating the 80 gradations of skill and muscular effort required in throwing the same and also adjusting the heights to which the rings are thrown the very best possible effects are secured in the physical, mental, and nervous development of the individuals playing the game employing my apparatus.

What I claim as my invention, and desire to secure by Letters Patent, is as follows, to wit:

1. In a game apparatus, the combination with a series of rings graduated in diameters, of the target-head made semicircular in form and slightly less in diameter than the smallest of said rings, the horizontal rod supporting 95 said target-head, and the field holding said rod and provided with means for its own suspension, substantially as and for the purpose set forth.

2. In a game apparatus, the combination 100 of the field, A, having means for its vertical adjustment, the rod, C, projecting therefrom, and the semicircular target-head carried by said rod, substantially as and for the purpose set forth.

3. In a game apparatus, the combination 105 of the supporting-rod, C, the target-head, B, and the ring, *d*, suspended from the said target-head, for the purpose set forth.

4. In a game apparatus, the combination 110 of the field, A, the rod, C, the target-head, B, the ring, *d*, suspended from said target-head, and the netting, E, attached to said ring and to said field, substantially as and for the purpose set forth.

5. In a game apparatus, the combination 115 of the target-head, B, the ring suspended therefrom, and the series of graduated throwing-rings, the largest of which is smaller than said ring *d*, and the smallest of which is larger than said target-head, substantially as and for the purpose set forth.

6. In a game apparatus, the combination 120 of the semicircular target-head, B, the hook, *b*, having retaining-spring, *b'*, and the ring, *d*, adapted to be removably suspended from said target-head by means of said hook, as and for the purpose set forth.

7. In a game apparatus, the combination 125 of the field, A, the cord, *a'*, pulley, *a*², the rod, C, and the target-head, B, for the purpose set forth.

8. In a game apparatus, the combination 130 of the circular field, A, having raised rim, A',

the series of rings, D, and the ring, d, all
adapted to be nested between said rim, the
removable target-head and rod, B, C, and the
netting, E, adapted to inclose said parts in
one compact bundle, as and for the purpose
set forth.

9. In a game apparatus, the combination
of the adjustable field, A, the rod, C, target-
head, B, having hook, b, the ring, d, adapted
to be suspended by said hook, and the netting,

E, attached to said ring, and to said field, sub-
stantially as and for the purpose set forth.

In testimony that I claim the foregoing in-
vention I have hereunto set my hand and seal
this 23d day of January, in the year 1897. 15

ANNE E. MORGAN. [L. S.]
